TRIGGER-LOCKING MEANS

Robert L. Jenkinson, New Haven, Conn., assignor
to The Marlin Firearms Co., New Haven, Conn.,
a corporation of Connecticut

Application April 23, 1946, Serial No. 664,240

1 Claim. (Cl. 42—70)

1

The present invention relates in general to firearms and more especially to firearms commonly known and classified as shotguns, the particular shotgun herein shown and described being a double-barreled shotgun of the over-and-under type.

Shotguns having double-barrels may employ two sets of fire-control mechanism including a trigger for each barrel. In using shotguns of this type in the field, a shooter quite generally engages both the first and second fingers of his hand with the front and rear triggers respectively of the shotgun in order to be ready to fire both barrels in rapid succession. However, it happens, not infrequently, that the shooter will inadvertently pull both triggers simultaneously, which not only wastes ammunition but produces an extremely severe recoil blow against the shooter's shoulder. Much has been written by way of explaining the cause of "doubling," and in general it may be said that the recoil and counter-recoil of the firearm plus the involuntary flinching and excitement of the shooter are contributing factors which may cause the simultaneous and inadvertent release of both triggers.

An object of the present invention is therefore to provide improved means for preventing the release simultaneously of both triggers of a double-barreled shotgun.

A further object is to provide improved trigger-locking means for a double-barreled shotgun having two triggers, the improved trigger-locking means being adapted to automatically lock one trigger when the second trigger is pulled.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a fragmentary side elevation partly in section of the frame structure of a double-barreled shotgun, including the improved trigger-locking means of this invention and a portion of the pistol grip;

Fig. 2 is a fragmentary plan view partly in section on line 2—2 of Fig. 1;

Fig. 3 is a fragmentary sectional elevation on line 3—3 of Fig. 1, showing both triggers in their normal positions;

Fig. 4 is similar to Fig. 3 but shows one of the triggers in its displaced position;

Fig. 5 is a perspective view of the left trigger;

2

Fig. 6 is a perspective view of the right trigger; and

Fig. 7 is a perspective view of the spacer.

In carrying out the invention, an exemplary embodiment of which is shown in the drawings, the frame 10 of the firearm has, at its forward end, a pivot-pin 11 for pivotally supporting the double-barrels (not shown) of the firearm, the barrels being of the over-and-under type adapted to be dropped at their muzzle-ends and raised at their breech-ends for inserting cartridges into the chambers of the barrels. The stationary breech-plate of the frame 10 is indicated generally at 12 and is an integral part of the frame structure 10. The trigger-guard 14 is shown as a separable element pinned at its forward end to a portion 15 of the frame structure, and secured at its rear end to the frame 10 by a screw 16 or similar fastening-means. The usual barrel unlocking-latch is shown at 17 pivotally mounted adjacent the crown of the frame 10. Rearwardly of the latch 17 is the conventional manually-operated safety 18.

The frame structure 10 also includes integral upper and lower tangs 19 and 20 respectively, joined at their rear ends by a post 21 which is integral at its opposite ends with the rear ends of the tangs 19 and 20. Between the rear post 21 and the stationary breech-plate 12 of the frame, is an intermediate-post 22 which is adapted, in a conventional manner, to slidably support the rear ends of the spring-loaded firing-pins (not shown) and to provide pivotal support for the trigger-sears, the latter being connected to the right- and left-hand triggers 23 and 24 respectively by sear-connectors 25 and 26 respectively. Suitable cover-plates are provided on opposite sides of the tangs 19 and 20 of the frame structure 10, as indicated at 47, in Figs. 1 and 2.

The triggers 23 and 24 comprise substantially-flat relatively-thin leaf-members (see Figs. 5 and 6) and are substantially identical in shape except that the finger-grip 27 of the right-hand trigger-member is nearer the forward end of the trigger than the finger-grip 28 of the left-hand trigger. The trigger-members are provided at their forward ends with pivot-pin holes 29 and 30 respectively, and adjacent their rear ends with notches 31 and 32 in their upper edges to receive the lower ends of the respective sear-connectors 25 and 26. Rearwardly of the notches are elongated apertures 33 and 34 respectively, the longitudinal axis of each aperture being disposed substantially transversely to the longitudinal axis of its trigger-member. The longitudinal apertures 33 and 34 are adapted to receive a fixed pin 35 and, as here-

inafter described, constitute relief-apertures to permit freedom of movement of the rear ends of the pivoted trigger-members.

At the rear extremity of each trigger-member and on the inner face thereof is a relatively-shallow concave circular-recess as shown at 36 and 37 respectively, each adapted to be in substantially-axial alignment with the other when the triggers are in assembled position in the frame structure 10, as shown in Figs. 2 and 3.

The triggers 23 and 24 are pivotally mounted adjacent their forward ends in a substantially-rectangular slot or aperture 38 (see Fig. 2) in the lower tang 20 of the frame structure 10 by a transverse-pin 39 which is mounted at its opposite ends in axially-aligned apertures at the forward end of the lower tang, the pin 39 passing through the axially-aligned holes 29 and 30 of the triggers. The triggers are thus arranged in substantially-spaced parallel relationship in the aperture 38. The triggers are adapted to be separated by a relatively-thin spacer-plate 40 which, as shown in Fig. 7, is apertured at its forward end, as at 41, to accommodate the transverse trigger pivot-pin 39; and adjacent its rear end, as at 42, to receive the fixed pin 35, the latter being mounted in axially-aligned apertures of the tang 20 of the frame structure transversely of the longitudinal axis of the rectangular aperture 38. The spacer-plate 40 is thus held securely in the rectangular aperture 38 substantially coincident with its longitudinal axis, the triggers 23 and 24 being free to move relative to the spacer-plate 40 by provision of the elongated relief-apertures 33 and 34 respectively through which the fixed pin 35 passes.

Although in the present embodiment the spacer-plate 40 is shown as a separate element, it will be understood that the plate 40 may be an integral part of the lower tang 20 of the frame structure.

As shown in Fig. 7, a third transverse aperture 43 is provided in the rear end of the spacer-plate 40. When the two triggers and the spacer-plate are assembled in their normal positions in the frame structure, the transverse aperture 43 is in axial alignment with the two shallow concave recesses in the inner faces of the respective triggers, as shown in Figs. 2 and 3. The diameter of the aperture 43 in the spacer-plate 40 and the diameters of the circular recesses 36 and 37 of the triggers are substantially equal, the aperture 43 and recesses 36 and 37 being adapted to receive a trigger-locking ball 44 which is of a diameter to make a smooth sliding fit in the aperture 43 and the recesses 36 and 37.

Referring to Fig. 3 in which the two triggers are in their normal positions, the axially-aligned recesses of the triggers and the aperture 43 in the spacer-plate form a closed pocket 45 for the ball 44, the latter being free to move transversely from the left to right or from right to left therein. The thickness of the spacer-plate 40 and the depth of each recess bear a predetermined relationship to the diameter of the ball such that when the ball is in either its extreme right- or left-hand position in the pocket, the periphery of the ball will clear the circumferential edge of the oppositely-disposed recess of the left and right triggers respectively. That is to say, the minimum effective length of the pocket 45 must be slightly greater than one and one-half times the diameter of the ball. The "effective length" of the pocket shall be understood to be the distance measured between the locus of all points on the

concave surface of the recess 36 engaged by the spherical surface of the ball, and the locus of all points on the conical surface of the recess 37 engaged by the spherical surface of the ball. The maximum effective length of the pocket 45 is a controlling factor in accomplishing the automatic displacement of the ball from either of its extreme positions in the pocket, the prerequisite being that the effective depth of each recess 36 and 37 shall be slightly less than the radius of the ball, so that when the ball is seated in the recess the center of mass of the ball, which coincides with its center of gravity will lie slightly outside of the circumferential edge of the recess. The term "effective depth" as applied to the recesses in the triggers shall be understood to mean the distance measured between the locus of all points on the conical surface of the recess engaged by the spherical surface of the ball and the circumferential edge of the recess.

In the operation of the triggers of the firearm, assuming the right- and left-hand triggers are in their normal positions, as indicated in Fig. 3, and that the trigger-locking ball 44 is seated in

the recess 37 of the left-hand trigger 24, the right-hand trigger 23 may be pulled without interference from the trigger-locking ball 44. Similarly, if instead of pulling the right-hand trigger 23 the left-hand trigger 24 is pulled, the wiping or camming action between the circumferential edge of the recess 37 of the left-hand trigger and the spherical surface of the ball will suffice to move the ball out of the recess 37, which action is effected by engagement of the edge of the recess with the spherical surface of the ball in a plane parallel to but offset from a plane through the center of gravity of the ball, the ball being free to move transversely across the pocket into the recess 36 of the right-hand trigger 23. A similar action takes place when the ball rests initially in the recess 36 of the right-hand trigger 23, as shown in Fig. 4.

Assuming, however, that the ball rests in the recess of the right-hand trigger and that the left-hand trigger 24 has been pulled and held in its retracted position as shown in Fig. 4, its recess 37 is then out of alignment with the adjacent end of the transverse aperture 43 of the pocket 45, thus presenting the inner substantially-plainer surface of the trigger-member 24 opposite the adjacent end of the transverse aperture 43, as a consequence of which the ball 44 is unable to move out of the recess 36 of the right-hand trigger 23 and will thereby effectively lock the right-hand trigger until the left-hand trigger 24 has been released and returned to its normal position. A similar action takes place to automatically lock the left-hand trigger when the right-hand trigger has been pulled.

The above described trigger-locking device is of relatively-simple construction embodying but one moving part and is adapted to be readily mounted in shotguns of the type described without necessitating any substantial alterations in the trigger-mechanism of the firearm, and at a minimum cost.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claim are intended to be embraced therein.

I claim:

In a firearm, the combination including: a frame; two trigger-members pivotally mounted for movement substantially vertically in said frame, said trigger-members having oppositely-disposed blind-recesses in the respective inner faces thereof and arranged side by side and in substantially-parallel laterally-spaced relationship, the said trigger-members having finger-gripping portions arranged in substantially-tandem relationship to each other; and trigger-locking means adapted to be operated automatically by pulling either trigger to lock the action of the other trigger, said locking-means comprising a spacer-plate fixedly secured in said frame between said trigger-members and having an aperture extending transversely therethrough substantially in axial alignment with the respective blind-recesses of said trigger-members, the said aperture of said spacer-plate and the respective blind-recesses of said trigger-members forming a substantially-transverse pocket extending between said trigger-members, and a ball mounted to roll freely in said pocket, the diameter of said ball corresponding substantially to the diameter of said pocket and to substantially two-thirds the transverse dimension thereof whereby movement

of one trigger-member vertically with respect to the opposite trigger-member and to said transverse aperture serves to cam said ball out of the blind-recess of said one trigger across said aperture into the blind-recess of the opposite trigger-member thereby automatically locking said oppositely-disposed trigger positively against movement while the blind-recess of said one trigger is out of alignment with the said transverse aperture.
